UNITED STATES PATENT OFFICE.

WILLIAM F. KIESEL, JR., OF ALTOONA, PENNSYLVANIA.

FRAME FOR RAILWAY-CARS.

No. 823,790.

Specification of Letters Patent.

Patented June 19, 1906.

Application filed August 23, 1905. Serial No. 275,388.

To all whom it may concern.

Be it known that I, WILLIAM F. KIESEL, Jr., a citizen of the United States, residing at Altoona, in the county of Blair and State of Pennsylvania, have invented certain new and useful Improvements in Frames for Railway-Cars, of which the following is a specification.

This invention relates to improvements in the steel end frame superstructure of railway-cars having vestibule-platforms; and the object of my improvements is to provide a light and stiff thoroughly-braced reinforcing-framework about which the wood framework and sheathing will be built up in such manner as to resist end shocks, as where cars are brought violently together in collision or otherwise, in order to prevent the crushing in of the vestibules or the telescoping of the cars. I attain my object by means of the construction and arrangement of the several parts of the framework, as illustrated in the accompanying drawings, in which—

Figure 1 represents a side elevation of the end of a vestibule-car with the sheathing and part of the wood framework omitted; Fig. 2, an end elevation of the same, one-half being shown in transverse section through the vestibule; Fig. 3, a plan view showing the top framework and a horizontal section through the vestibule above the platform; Fig. 4, a vertical longitudinal section through the center of the upper portion of the vestibule; Fig. 5, a plan view of the metal vestibule-ceiling and roof-framework, and Fig. 6 a side elevation of the same.

Like numerals designate like parts in the several views.

The superstructure of the car, as herein illustrated, rests upon a box-girder 1, which extends from end to end of the car and projects out under the platforms. At the end of the car-body cantaliver end-sill plates 2 project from each side of the center sill, and at the extreme end of the center sill is the platform end sill 3. Corner-posts of Z-shaped cross-section rise at 4 from the extremities of the end sills 2, and from each side of the platform end sill rise angle corner-posts 5, said corner-posts 4 and 5 being riveted at the top to the ends of short top side plates 6. At the sides of the car are vertical plates 7, riveted to the corner-posts 4 and stiffened at their inward sides by angle-bars 8, said angles being bent inwardly from a point below or on a line with the window-sills and having their

feet flattened and riveted to the side sills of the metal underframe, which, as herein shown, are formed of the angle-bars 10. Gusset-plates 9 are riveted in the spaces between the bend of the angle-bars 8 and the vertical plates 7. The plates 7 and the reinforcing angle-bars 8 extend up to the top of the car, where they form inward continuations of the top side plates 6. These brace-plates on each side of the car add very materially to the stiffness of the corner-posts 4 and through the top side plates 6 brace the vestibule corner-posts 5 and prevent the longitudinal displacement of said posts. At each side of the car-door are door-posts 11, also of Z-shaped cross-section, with their feet riveted to the side sills 2, and from a point near the foot of these posts diagonal brace-bars 12 extend to the top of the corner-posts 4, these diagonal brace-bars being also of Z-shaped cross-section, which in the case of both posts and braces facilitates the attachment of the wood-work thereto and also provides a light, stiff, and strong skeleton framework. The corner-posts, door-posts, and diagonal braces are riveted at their upper ends to the arched top plate 14, which passes across from corner-post to corner-post through the car-body end frame. A similar arched top plate 15 passes across between the vestibule corner-posts 5, said plate being bent outwardly to conform with the curve of the end of the vestibule. Between these front and back top plates is the vestibule ceiling-sheet 16, which is riveted to the top plates by means of the angle-bars 18 and 17, respectively. This ceiling-plate has the corners cut off diagonally, and these diagonal edges are stiffened by means of angle-bars 19, riveted thereto. The ceiling-plate at each side back of the diagonal cuts is flanged downwardly and riveted to the top side plates 6. By this construction it will be seen that the center of the vestibule-top is thoroughly braced from the corner-posts 4 and the corner-post braces 7 through the ceiling-plate and the diagonal angle-bars 19. The ventilator side plates 22 at the ends are attached to and supported by the back top plates 14 by means of the angle brace-plates 20, which have vertical flanges to receive said ventilator side plates and have their inclined inner edges flanged to further stiffen them. The extreme outer ends of the ventilator side plates are secured to the front top plate angle 18 by means of the short angle-braces 21, riveted thereto.

From the door-posts 11 channel-bars 23 project forwardly under the ceiling-plate to the front top plate 15, said channels being flanged at each end and riveted to the back 5 and front top plates with the top longitudinal flanges riveted to the ceiling-plate. These channels are further strengthened by angle-bars 24, and the spaces between the angles and the lower flanges of the channels serve 10 as guideways and housings for the upper vestibule buffer stems and springs, said stems passing in through openings provided therefor in the vestibule-door casing and top front plate 15, as shown in the left-hand portion of 15 Fig. 2.

The ceiling-plate is reduced somewhat in weight without detracting from its strength by cutting holes therein at each side between the diagonal angles 19 and the channels 23. 20 In the center a hole is provided to accommodate the vestibule-lamp.

At each side of the center sill brace-bars 25 extend between the end sills and the platform end sills. This latter construction, however, forms part of the underframe construction and is claimed, together with the particular form of center sill, end sill, and platform end sill, as herein illustrated, in another 25 application.

30 By this construction of the frame members it will be seen that the vestibule at top and bottom is thoroughly braced against longitudinal and transverse strains, the corner-posts for both car-body and vestibule being braced longitudinally by the corner-post brace-plates at the sides of the car-body, the car-body corner-posts being braced transversely by the angle-braces 12 and the vestibule corner-posts being braced transversely at the 35 top by the ceiling-plate and top frame members.

In the several views I have indicated the manner of building up the wood framework and sheathing around the metal framework, 45 and the further advantages attained by my construction will be apparent to those skilled in the art from an inspection of the said drawings.

What I claim as my invention, and desire 50 to secure by Letters Patent, is—

1. In a car-frame, the combination, with the corner-posts and side sills, of vertical brace-plates rising from the side sills at the back of the posts, angle-bars riveted to the 55 brace-plates at their inward edges, said angle-bars being inclined away from the plates at their lower ends, and gusset-plates filling the spaces made thereby, said brace-plates, gusset-plates and angle-bars being attached along 60 their base sides to the side sills.

2. In a car-frame, the combination, with the car-body end sills, side sills and platform end sills, of corner-posts rising from the car-body end sills and from the platform end sills, 65 top side plates extending between and join-

ing the corner-posts at each side, front and back top plates extending across between posts on opposite sides, horizontal brace members extending from the car-body corner-posts at the top to intermediate points on the 70 front top plate, and brace-plates rising from the side sills back of the car-body corner-posts.

3. In a car-frame, the combination, with the car-body end sills, side sills and platform 75 end sills, of corner-posts rising from the car-body end sills and from the platform end sills, top side plates extending between the corner-posts at each side, front and back top plates extending across between posts on opposite 80 sides, and a ceiling-plate extending between the front and back top plates.

4. In a car-frame, the combination, with the car-body and vestibule corner-posts, of top side plates extending between the posts 85 at each side, front and back top plates extending across between opposite posts, and a ceiling-plate extending between the front and back top plates, said ceiling-plate having its front corners cut off diagonally and reinforced by angle-bars and its sides, back of 90 the diagonal cuts, riveted to the top side plates.

5. In a car-frame, the combination, with the car-body and vestibule corner-posts, of 95 top side plates extending between the posts at each side, front and back top plates extending across between opposite posts, a ceiling-plate extending between the front and back top plates, and longitudinal brace-bars 100 extending between the front and back top plates and attached to the under side of the ceiling-plate.

6. In a car-frame, the combination, with the car-body and vestibule corner-posts and 105 car-body door-posts, of top side plates extending between the car-body and vestibule corner-posts at each side, front and back top plates extending across between opposite posts, the door-posts being united at the top 110 to the back top plate, longitudinal braces extending from the back top plate where the door-posts are attached thereto to the front top plate, and a ceiling-plate extending between the front and back top plates and attached to the longitudinal braces. 115

7. In a car-frame, the combination, with the corner-posts 4 and 5 and the brace-plates 7, of the top side plates 6, the arched front and back top plates 15 and 14, the ceiling-plate 16 cut diagonally at each side and reinforced by angles 19, the arched angle-bars 18 and 17 riveted to the front and back top plates and uniting the ceiling-plate thereto, the door-posts 11 united at the top to the 120 back top plate, and the channel-braces 23 extending from the door-posts to the front top plate and riveted to the under side of the ceiling-plate. 125

8. In a car-frame, the combination, with 130

the car-body and vestibule corner-posts, of front and back top plates extending across between opposite posts, ventilator side plates passing over the back top plate and having their ends attached to the front top plate, and transverse angle-braces between the back top plate and the ventilator side plates.

5 9. In a car-frame, the combination, with the end door-posts and vestibule door-posts, of longitudinal braces extending between their upper ends and provided with guideways for the upper buffer stems and springs.

10. In a car-frame, the combination, with the end door-posts and vestibule door-posts, 15 and the vestibule ceiling-plate, of longitudinal channels riveted to the under side of said plate between posts, said channels having longitudinal angles riveted to their webs on the flanged side for the purpose set forth.

20 11. In a car-frame, the combination, with a continuous center sill, of a car-body end sill comprising vertical plates projecting

from each side of the center sill back of the end, a platform end sill passing across the end of the center sill and supported thereby, 25 longitudinal braces extending between the car-body end sill plates and the platform end sill at each side of the center sill, posts rising from the ends of the car-body and platform end sills, top side plates extending between 30 posts at each side of the car, a ceiling-plate passing across between the top side plates, a front, or end top plate passing across between the ends of the top side plates and riveted to the outer edge of the ceiling-plate, 35 and longitudinal braces riveted to the under side of the ceiling-plate at each side of the center.

In testimony whereof I have affixed my signature in presence of two witnesses.
